GEORG DANZER, OF PLAUE, GERMANY, ASSIGNOR TO THE FIRM VOGTLANDISCHE MASCHINENFABRIK (VORM. J. C. UND H. DIETRICH) A.-G., OF PLAUE, GERMANY

CUTTING AND TRANSFERRING MECHANISM FOR PRINTING PRESSES

Application filed May 26, 1928, Serial No. 280,891, and in Germany July 15, 1927.

My invention relates to rotary (web) printing presses and more especially to improvements in the cutting and collecting devices of machines of this kind.

It is a fact well known among practitioners in the art of designing and building rotary printing machines that the problem of transferring the printed web or sheets respectively from the cutting device to the collecting mechanism has always presented considerable difficulties. The latter have not been satisfactorily overcome in practice with the means usually applied for transferring the sheets, viz needles and travelling endless conveyer bands—because of the paper being mutilated by the punctures from said needles and the printed surfaces being liable to become stained and smutted by the conveyer bands.

I have tried to remove the said drawbacks by providing at the grooved cylinder of the cutting mechanism a pair of lateral grippers by which the printed sheets were temporarily held in position near their bottom edge; but it was impossible to hold the sheets by said grippers during the whole transferring action, viz. until they were caught by the grippers of the collecting cylinder, because of the latter being arranged at a distance of several millimeters away from the grooved cylinder of the cutting mechanism.

Thus—by reason of the printed sheets not being securely guided while travelling over the gap between the grooved and the collecting cylinder, it frequently happens with machines running at full speed that because of the web pushing from behind the sheets are considerably creased and wrinkled, so as to interfere with the proper working of the collecting and folding devices and to entail various other troubles.

For this reason the attendants were often compelled to slow down the running speed of the cutting and collecting devices, and in turn the working speed of the whole rotary printing press, thereby considerably impairing the output of the latter; for reasons of economy however only in comparatively few cases in which rather costly prints were to be delivered without the slightest mutilation, the grooved cylinder of rotary printing

presses was provided with a gripping mechanism of the kind indicated above for assisting in transferring the sheets.

The object of my invention is to remove the disadvantages described above and to provide improved means for safely and positively guiding the sheets on their whole way from the cutting to the collecting device until they are delivered to the latter, while the whole machine runs at full speed.

The nature and scope of my invention is briefly outlined in the appended claims and will be more fully understood from the following specification taken together with the accompanying drawing in which

Fig. 1 shows diagrammatically the cutting and collecting mechanism of a rotary printing press;

Fig. 2 is a longitudinal section through the grooved cylinder of a cutting device designed according to this invention;

Fig. 3 is a cross sectional view of the grooved cylinder of the cutting device taken from the end opposite to that of Fig. 1.

The printed webs while jointly travelling downward, as indicated at 1 in Fig. 1, are delivered in the usual manner to the cutting mechanism and are cut by the knife carrying cylinder 2 and the grooved cylinder 3 into single sheets or batches of sheets respectively, the latter being clamped at both sides near the cutting line and pressed against the grooved cylinder 3 by a pair of lateral grippers 5 as seen in Figs. 2 and 3.

A fluted or corrugated roller 7, diagrammatically indicated in Fig. 1 and revolving at a speed greater than the circumferential speed of the cylinders 2, 3 is provided for guiding and pushing forward the lower part of the sheet towards the collecting cylinder 6, the latter rotating at a ratio equal to that of the cylinders 2 and 3. This ratio of rotation between the roller 7 and the cylinders 2 and 3 is obtained by the employment of a suitable transmission means, such as a set of gears 6', 33 and 7' indicated by dotted lines in Fig. 1. By the said fluted roller 7 the lower part of the sheet is positively bent around and kept in close proximity to the grooved cylinder 3 so as to pass over a set of

guide fingers 8 attached to a bar 9, the latter being mounted on the machine frame. Under the control of said guide fingers 8 the sheets will pass on to the collecting cylinder 6, by 5 the gripping mechanism of which (not shown) the sheets are firmly clamped at their bottom edge and carried forward.

Another set of guiding fingers 10, being attached to a bar 11 which is mounted on the 10 machine frame, is provided for supplementing the guiding action viz. by stripping off the sheets—whenever necessary—from the grooved cylinder 3.

Inasmuch as the printed sheets of paper 15 must be released at their lower end by the lateral grippers 5—referred to above—not later than at point 15, indicated in Fig. 1, and as the sheets—not until having reached point 16—are caught by the gripping device of cylinder 6, nothing would insure their safe 20 delivery from points 15 to 16 except the sheet's own rigidity, which however can obviously not be relied upon especially in the case of thin, pliable paper and in view of 25 the lack of stiffness resulting from the curved form of the sheets in transit.

According to this invention an auxiliary set of lateral grippers 17 is provided at the 30 grooved cylinder 3 in addition to the grippers 5 in order to assist in and safeguard the whole 35 transferring action, until the sheets have actually reached the collecting mechanism 6.

The actuating mechanism of both sets of 35 grippers 5 and 17 closely resemble each other in their design. Said actuating mechanism 40 comprises oscillating spindles 18, which are mounted in recesses of the cylinder 3 and have bevel gear wheels 19, 20 attached to them, as seen in Figs. 2 and 3.

45 Levers 22, carrying sliding rollers 21 at their outer ends and being rigidly mounted on corresponding ends of said spindles 18, cooperate with a curved face-cam 24, which is stationarily fixed on the machine frame 50 and controls the movements of both said levers 22, so that the spindles 18 and gear wheels 19, 20 respectively are given an oscillatory motion at each revolution of the grooved cylinder 3.

55 The grippers 5 and 17 are mounted on carrier members which are operated by bevel wheels 25 and 26 respectively, the latter being geared to the wheels 19, 20 and mounted in recesses of the cylinder 3; by reason of 60 both sliding rollers 21 running in one and the same stationary face-cam 24 the respective sets of grippers 5 and 17 are opened and closed at corresponding places while the cylinder 3 revolves, viz. being pressed against 65 the cylinder 3 at point 4 and released at 15 in Fig. 1.

The mode of operation is as follows:—

The head gears 19 and 20 are each fixed to 70 the spindle 18, while the gears 25 and 26 are 75 the gears meshing with the said first named

gears and which carry the grippers 5 or 17. The levers 22 are crank arms fixed to the ends of the spindles 18 and are each provided with a crank pin on its free ends on which a roller 21 is mounted. The said roller engages an 70 annular cam groove in the stationary member 24. Therefore as the grooved cylinder 3 revolves each spindle 18 will be rotated with the latter but not around itself while the corresponding roller 21 just rolls in one portion 75 of the cam groove. At certain intervals, because of a change in the cam groove, the crank arms will be caused to oscillate and consequently transmit this oscillatory motion to the shafts 18 and consequently the gears 19 80 and 20, which, in turn, will impart to the bevel gears 25 and 26 a partial rotation. As a result thereof the grippers 5 and 17 will be alternately lifted from and lowered onto the bearing surfaces 27.

85 Means are provided for altering the distance of the grippers of each set so as to cope with the respective requirements in printing webs of different width: As seen in Figs. 2 and 3 a sleeve 29 is slidably attached 90 to the shaft 28 of the cylinder 3 by means of a key 30 so as to rotate with the cylinder 3 and to be capable of being shifted longitudinally to the latter.

95 Said sleeve 29 and the grippers attached thereto can be fixed by means of a clamping screw 31 in any desired position relatively to the cylinder 3, the latter being provided with an annular recess 33 for obvious reasons.

100 Abutment members 27 with which the respective grippers 5 and 17 cooperate and the bearings of the bevel gear wheels 26 are also attached to the sleeve 29 and are simultaneously shifted with the latter. The other bevel gear wheels 20, being slidably mounted on the spindles 18 by means of a key 40, are held in their proper place by abutting at the rear against an extension 32 of the sleeve 29 and by meshing at their business end with 110 the corresponding bevel gear wheels 26.

115 By the means described above the gripper 5 (at the right) and its actuating mechanism can be shifted to 5'—indicated in Fig. 2—or to any intermediate place, so as to securely hold and transfer sheets of papers the width of which range from x to y inches.

120 Various changes and modifications may be made in the design and cooperation of the above described mechanism for transversely cutting the printed web and transferring the sheets to the collecting cylinder of rotary printing presses without substantially deviating from the spirit and the leading ideas of 125 my invention.

130 Thus e. g. instead of two sets of grippers 5 and 17, designed for safely transferring the printed sheets to the collecting cylinder 6, a series of three or more sets of grip-

pers may be provided on the cylinder 3 for the same purpose.

What I claim is:

1. Mechanism for transferring the cut sheets from the cutting cylinders to the collecting device of rotary printing presses comprising a plurality of sets of lateral grippers being mounted on one of the cutting cylinders, said grippers being operatively interconnected and adapted to securely hold the cut sheets until the latter have been actually engaged by the grippers of the collecting device.

2. Mechanism for transferring the cut sheets from the cutting cylinders to the collecting device of rotary printing presses comprising in combination a plurality of sets of lateral grippers being mounted on one of the cutting cylinders, said grippers being operatively interconnected and adapted to securely hold the printed sheets until the latter have been actually engaged by the grippers of the collecting device and means for guiding the cut sheets in transit to the collecting device.

3. Mechanism for transferring the cut sheets from the cutting cylinders to the collecting device of rotary printing presses comprising in combination a plurality of sets of lateral grippers being mounted on one of the cutting cylinders, said grippers being operatively interconnected and adapted to securely hold the printed sheets until the latter have been actually engaged by the grippers of the collecting device, and means for guiding the cut sheets in transit to the collecting device, said means comprising a fluted roller, revolving at a speed greater than the grooved cylinder and sets of fingers, adapted to support the sheets and strip off respectively the latter from the grooved cylinder.

4. Mechanism for transferring the cut sheets from the cutting cylinders to the collecting device of rotary printing presses comprising in combination a plurality of sets of lateral grippers being mounted on one of the cutting cylinders, said grippers being operatively interconnected and adapted to securely hold the printed sheets until the latter have been actually engaged by the grippers of the collecting device, and means for altering the distance of the grippers of each set of lateral grippers so as to adjust said mechanism to webs of different width.

5. Mechanism for transferring the cut sheets from the cutting cylinders to the collecting device of rotary printing presses, comprising in combination a plurality of sets of lateral grippers being mounted on one of the cutting cylinders, said grippers being operatively interconnected and adapted to securely hold the printed sheets, until the latter have been actually engaged by the grippers of the collecting cylinder, means for guiding the cut sheets in transit and means for altering the distance of the grippers of each set of

lateral grippers, so as to adjust the mechanism to webs of different width, said means comprising a sleeve slidably arranged on the shaft of the grooved cylinder and carrying the respective grippers and their respective actuating members.

6. Mechanism for transferring the cut sheets from the cutting cylinders to the collecting device of rotary printing presses, comprising in combination a plurality of sets of lateral grippers being mounted on one of the cutting cylinders, said grippers being operatively interconnected and adapted to securely hold the printed sheets, until the latter have been actually engaged by the grippers of the collecting cylinder, means for guiding the cut sheets in transit, means for altering the distance of the grippers of each set of lateral grippers so as to adjust the mechanism to webs of different width, said means comprising a sleeve, slidably arranged on the shaft of the grooved cylinder and carrying the respective grippers and their respective actuating members, and means for guiding the cut sheets to the collecting device.

7. Mechanism for transferring the cut sheets from the cutting cylinders to the collecting device of rotary printing presses comprising in combination a plurality of sets of lateral grippers being mounted on one of the cutting cylinders, said grippers being operatively interconnected and adapted to securely hold the printed sheets until the latter have been actually engaged by the grippers of the collecting cylinder, means for altering the distance of the grippers of each set of lateral grippers, so as to adjust the mechanism to webs of different width, said means comprising a sleeve, slidably arranged on the shaft of the grooved cylinder and carrying the respective grippers and their respective actuating members, and means for guiding the cut sheets to the collecting device.

8. Means for transferring the cut sheets from the cutting cylinders to the collecting device of a printing press comprising a plurality of sets of grippers mounted on one of the cutting cylinders, and means to operate said grippers to securely hold the cut sheets until the latter have been engaged on the collecting device.

In testimony whereof I affix my signature.
GEORG DANZER.
